H. V. BASLEY,
HOLDER FOR IRONING BOARDS AND THE LIKE,
APPLICATION FILED SEPT. 18, 1916.
1,276,611.

Patented Aug. 20, 1918.

UNITED STATES PATENT OFFICE.

HARVEY V. BASLEY, OF JERSEY CITY, NEW JERSEY.

HOLDER FOR IRONING-BOARDS AND THE LIKE.

1,276,611.

Specification of Letters Patent. Patented Aug. 20, 1918.

Application filed September 18, 1916. Serial No. 120,630.

To all whom it may concern:

Be it known that I, HARVEY V. BASLEY, residing at Jersey City, in the county of Hudson and State of New Jersey, have invented certain new and useful Improvements in Holders for Ironing-Boards and the like, of which the following is a specification.

This invention relates to a holder or bracket adapted for conveniently and detachably supporting ironing boards and the like and the object of the invention is to provide a holder or bracket which will be simple, strong and efficient for its purpose and which may be manufactured at small cost.

A further object is to provide a holder or bracket which may be readily adjusted to accommodate itself for supporting ironing boards and the like of various sizes, and to provide attaching means for the bracket adapted to retain the bracket in any adjusted position.

A more detailed object is to provide a bracket which is made preferably from a single length of wire bent to form all of the necessary and desirable elements of the device.

A further object is to provide a support or bracket of the type indicated which comprises a pair of arms, and to so shape and form the arms that they will be resilient of a desirable extent for improving the gripping action upon the ironing board or the like.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention:

Figure 1 is a front elevational view of a bracket constructed in accordance with the provisions of this invention, illustrating the same in use supporting an ironing board.

Fig. 2 is an enlarged top plan view of the bracket shown in Fig. 1.

Fig. 3 illustrates a modification.

Referring to the drawings for a detailed description of the structures which are illustrated therein, the reference character L indicates an ironing board. The reference character G indicates the bracket which is adapted to be connected to one surface of a door, wall, or other appropriate support, by means of screws H.

The bracket is formed of a single length of wire shaped to provide two halves or arms 1 and 2 of identical shape. The wire is bent, or crooked, at a point 3 intermediate the arms 1 and 2 for defining a proper and appropriate point whereby the wire may be readily bent in adjusting the arms with respect to each other. The portion 3 thereby constitutes a desirable integral hinge section.

Each arm constitutes an upper lead 4 and a lower lead 5, said leads being provided by bending the outer ends of the wire upon themselves, as clearly seen in Fig. 1. The end portion of the lower lead is bent downwardly to form a brace leg 6 and the extreme end of this leg is bent to form an eye 7.

An eye 8 is formed in the upper lead of each arm adjacent the hinge section 3, said eye 8 being formed by bending an upwardly extending loop in the wire, as clearly indicated in Fig. 1.

The eyes 7 and 8 are intended to receive the screws H.

The outer end portions of the arms 1 and 2 are bent outwardly at right angles to the major portion of said arms, as at 9, to form shoulders against which the inclined edges 10 of the ironing board may engage. The outer ends of the portion forming the shoulders 9 are provided with inturned fingers 10^a for engaging over a relatively outer surface of the ironing board to retain the ironing board against accidental displacement, as will be clearly seen from an inspection of Fig. 2.

In order to adjust the device for ironing boards of different widths it is simply necessary to bend the arms upwardly or downwardly about the hinge section 3 as a pivot. Upward movement of the arms will move the shoulders 9 farther apart for accommodating wider boards, while downward movement will bring the shoulders 9 closer together for accommodating boards of a less width. The brace legs 6 may also be bent

with respect to the remainder of the arms at points indicated at 11 so as to readily dispose said brace legs in the most appropriate bracing position according to the angle 5 of incline of the arms.

The upper leads 4 of each arm is preferably bent intermediate its length, as at 12, so as to improve the appearance of the device and so as to provide a slight degree of 10 resiliency in said upper leads in the direction of the length of the arms so that when weight is applied to the shoulders 9 and is resisted by the upper ends of the brace legs 6 engaging the upper leads 4 at the points 15 11, the shoulder portions 9 will be permitted to have a slight twist inwardly toward the edges of the ironing board. By this means the shoulder portions 9 are caused to engage or bite slightly into the edges of the ironing 20 board.

Although I have illustrated and described this device to be formed of wire, it will nevertheless be apparent that the broad idea embodied therein, namely that of providing 25 opposing shoulder portions which are adjustable with respect to each other for gripping opposite edges of ironing boards or the like of different widths, may be attained by the use of other materials, or by the use of 30 devices having detail structural characteristics different from those illustrated and described therein.

As many changes could be made in this construction without departing from the 35 scope of the following claims, it is intended that all matter contained in the above description or shown in the accompanying drawing shall be interpreted as illustrative only and not in a limiting sense.

40 At the point 3 the wire comprising the device may be treated or operated upon in any desired manner for improving the hinged action, but for example it is shown in the drawings as being made thinner at 45 this point, as is best seen in Fig. 1.

It should be noted that since the eyes for receiving the screws H are formed of wire, naturally a desirable countersink opening is provided for receiving the screw head.

50 In the modification Fig. 3, one of the arms is illustrated and the shoulder portion 9 thereof is provided with an anti-friction roller 13. By providing such a roller upon each of the shoulders 9, likelihood of mutilation of the edges of the ironing board, and particularly of the ironing board covering is avoided.

Having thus described my invention what I claim as new and desire to secure by Letters Patent is:

65 1. A support for ironing boards or the like, comprising a member formed of a single length of wire bent to form a pair of arms and brace legs for said arms all lying in a common plane, and the outer ends of

said arms being bent to form shoulders at right angles to said common plane for engaging the opposite edges of the ironing board.

2. A support for ironing boards or the like, comprising a member having a part adapted to be attached to a support and to span the width of the ironing board, and having opposing shoulders formed therein for engaging opposite edge portions of the ironing board, and anti-friction rollers provided upon said shoulders for the purpose set forth.

3. A carrier for ironing boards or the like, comprising a member formed of a single length of wire shaped to provide an attaching portion adapted for spanning the width of the ironing board and by which the member may be fixed to a support, to provide portions comprising shoulders adapted for engaging the opposite edges of the ironing board, and to provide portions comprising brace legs extending from adjacent said shoulders and having means whereby they may be fixed to the support.

4. A carrier for ironing boards or the like, comprising a member having a part adapted to be attached to a support and to span the width of the ironing board and having opposing shoulders formed thereon for engaging the opposite edges of the ironing board, said part being of a character to be attached by its intermediate portion to said support and also being of a character that the mentioned shoulders thereof tend to move toward each other when weight is applied thereto by the ironing board.

5. A carrier for ironing boards or the like, comprising a member adapted to be attached to a support and to span the width of the ironing board, and having opposing shoulders formed thereon for engaging the opposite edges of the ironing board, said member including two portions one for carrying each of said shoulders, said member having attaching means intermediate said shoulders and the two mentioned portions thereof inclining downwardly from the region of the attaching means and carrying the shoulders in a plane below the attaching means.

6. A carrier for ironing boards or the like, comprising a member adapted to be attached to a support and to span the width of the ironing board, and having opposing shoulders formed thereon for engaging the opposite edges of the ironing board, said member including two portions one for carrying each of said shoulders, said member having attaching means intermediate said shoulders, the two mentioned portions thereof inclining downwardly from the region of the attaching means and carrying the shoulders in a plane below the attaching means, and a pair of brace legs one extending downwardly

from each of said portions and each having attaching means whereby it may be attached to the support.

7. A carrier for ironing boards or the like, comprising a member adapted to be attached to a support and to span the width of the ironing board, and having opposing shoulders formed thereon for engaging the opposite edges of the ironing board, said member including two portions one for carrying each of said shoulders, said member having attaching means intermediate said shoulders, the two mentioned portions thereof inclining downwardly from the region of the attaching means, and a pair of brace legs one extending downwardly from each of said portions and each having attaching means

whereby it may be attached to the support, and all of said parts being formed of a single length of wire, said wire being bent 20 substantially midway in its length to provide the first mentioned attaching means, being bent upon itself near its opposite ends to provide the shoulders providing double thickness for forming the shoulders, and the 25 opposite end portions of said wire being bent diagonally downwardly from adjacent the shoulders so as to provide the brace legs.

In testimony whereof I affix my signature in the presence of two witnesses.

HARVEY V. BASLEY.
